UNITED STATES PATENT OFFICE.

RICHARD MOELLER AND OSCAR OTTERSON, OF MICHIGAN CITY, INDIANA.

CRUDE-OIL-BURNING FURNACE.

1,417,092.

Specification of Letters Patent. Patented May 23, 1922.

Application filed August 13, 1920. Serial No. 403,435.

To all whom it may concern:

Be it known that RICHARD MOELLER and OSCAR OTTERSON, citizens of the United States, residing at Michigan City, in the 5 county of Laporte, State of Indiana, have invented a new and useful Crude-Oil-Burning Furnace; and they do hereby declare the following to be a full, clear, and exact description of the invention, such as will enable others skilled in the art to which it 10 appertains to make and use the same.

The invention relates to crude oil burning furnaces, particularly adapted for heating metal for welding or other purposes and has 15 for its object to provide a device of this character wherein oil is projected into a combustion chamber which extends from one side of a heating chamber to a point above the heating chamber and is in communication 20 with the heating chamber by a vertically disposed passage or flue, in which the metal may be placed for heating purposes. By projecting the blast into a combustion chamber, it will be seen that all particles of 25 the oil will be burnt and the products of combustion completely consumed, said products being consumed before they enter the heating chamber.

A further object is to provide a metal 30 heating furnace wherein the blast enters the heating chamber at an angle where the flames will not be projected through the furnace opening, thereby allowing an operator to come close to the furnace opening without 35 being burnt.

With the above and other objects in view the invention resides in the combination and arrangement of parts as hereinafter set forth, shown in the drawings, described and 40 claimed, it being understood that changes in the precise embodiment of the invention may be made within the scope of what is claimed without departing from the spirit of the invention.

45 In the drawings:—

Figure 1 is a front elevation of the furnace.

Figure 2 is an end view, showing the burner aperture.

Figure 3 is a longitudinal vertical sectional view through the furnace.

Figure 4 is a transverse sectional view taken on line 4—4 of Figure 3.

Referring to the drawings, the numeral 1 designates a rectangular shaped metallic

casing, in which refractory material is 55 placed for forming the furnace. The casing 1 comprises the bed plate 2 which is secured by means of bolts 3 to supporting legs 4, which supporting legs support the furnace as a whole spaced from the ground. Secured to the forward and rear edges of the bed plate 2 by means of bolts 5 are the front and rear sides 6 and 7 of the casing, said sides 6 and 7 being provided with reinforcing ribs 8 which preventing buckling of the 60 sides incident to intense heat. The ends of the casing 1 are also formed from metal, said ends being designated by the numerals 9 and 10. Ends 9 and 10 are provided with flanges 11, through which flanges and 65 through elongated apertures 12 in the ends of the front and rear sides 6 and 7 tie rods 13 extend, by means of which tie rods the metallic casing 1 is held together, the elongated apertures 12 allowing longitudinal expansion of the refractory material herein- 70 after described, which is disposed within the casing 1.

The furnace passages and combustion chamber are formed either by a solid material, or any other way, however it is preferably formed from refractory brick, thereby allowing the furnace to be quickly built and repaired.

The furnace comprises a heating chamber 85 14, which heating chamber is preferably located adjacent one end of the furnace as a whole and extending upwardly from the heating chamber 14 is a vertically disposed 90 passage of communication 15, through which passage a blast of fire passes downwardly into the heating chamber 14 from the end 16 of the combustion chamber 17, thereby preventing the entrance of the blast into the heating chamber at an angle where it will be 95 projected through the furnace opening 18 which would prevent an operator closely approaching the furnace opening 18. The combustion chamber 17 extends towards the end 9 and is provided with a downwardly 100 extending portion 19 which terminates substantially centrally of the end 9 and in registration therewith is the burner aperture 20 in the plate 9. Disposed in the burner aperture 20 is a conventional form of oil 105 burner 21 which burner projects oil into the portion 19 of the combustion chamber where it is ignited. The flame or blast passes

through the elongated combustion chamber thereby causing the combustion of all the oil projected before it passes into the heating chamber 14 where it comes into contact 5 with the article being heated. It will be seen that the blast is not a direct blast on the metal, therefore the metal will not become coated with oil which prevents the rapid heating of the metal. By consuming all of 10 the oil in the combustion chamber it will be seen that the products of combustion such as gases will be consumed and will not leave the furnace.

The top of the combustion chamber 17 is 15 formed with a transversely disposed arch 22 which arch is held together by bars 23 which engage the upper side of the arch and are provided with downwardly extending lugs 24 in which set screws 25 are threaded, said 20 set screws forming means whereby the longitudinally disposed arch engaging bars 26 are forced into engagement with the sides of the arch for holding said arch against falling, incident to extreme heat which will 25 cause expansion. It will be noted that the arch member may be easily removed for examining the interior of the furnace and for repairing the same.

When it is desired to light the furnace, 30 this may be accomplished through the burner opening 20.

The invention have been set forth what is claimed as new and useful is:—

A furnace comprising a heating chamber and an elongated combustion chamber, one 35 end of said combustion chamber being disposed above the heating chamber and having a passage of communication vertically disposed with the heating chamber, said combustion chamber extending downwardly to 40 one side of the heating chamber, means for projecting fuel into the downwardly extending end of the combustion chamber, a metallic casing for the furnace comprising bottom, end and side plates, an aperture in one 45 of the end plates in registration with the downwardly extending end of the combustion chamber for the reception of a burner, transversely disposed clamping members for holding the upper end of the furnace, and 50 means whereby the metallic sides and ends may move in relation to each other incident to expansion.

In testimony whereof we have signed our names to this specification in the presence of 55 two subscribing witnesses.

RICHARD MOELLER.
OSCAR OTTERSON.
